UNITED STATES PATENT OFFICE.

LIBERTY K. FLANAGAN AND CHARLES A. MILLER, OF MOBERLY, MISSOURI.

FLASH-LIGHT.

1,013,287.

Specification of Letters Patent.

Patented Jan. 2, 1912.

Application filed April 29, 1910, Serial No. 558,352. Renewed May 23, 1911. Serial No. 629,062.

To all whom it may concern:

Be it known that we, LIBERTY K. FLANAGAN and CHARLES A. MILLER, citizens of the United States, both residing at Moberly, in the county of Randolph and State of Missouri, have invented certain new and useful Improvements in Flash-Lights, of which the following is a specification.

This invention relates to flash lights and more particularly to that class of flash light especially designed for use in taking photographs.

The object of the invention is to provide a flash light, the construction of which is such that the torch may be adjusted vertically of the supporting stand and the powder spread on the flame by air pressure.

A further object is to provide a flash light including a plurality of telescopic sections, one of which is provided with a powder receiving receptacle and a laterally extending arm adapted to support a torch, means being provided for forcing a current of air through the telescopic sections into the powder receiving receptacle for spreading the powder on the torch,

A still further object of the invention is generally to improve this class of devices, so as to increase their utility, durability and efficiency.

Further objects and advantages will appear in the following description, it being understood that various changes in form, proportions and minor details of construction may be resorted to within the scope of the appended claims.

For a full understanding of the invention and the merits thereof, reference is to be had to the following description and accompanying drawings, in which:

Figure 1 is a side elevation of a flash light constructed in accordance with our invention; Fig. 2 is a vertical sectional view of a portion thereof; Fig. 3 is a detail perspective view of the spreading nozzle detached; Fig. 4 is a side elevation illustrating a modified form of the invention.

Corresponding and like parts are referred to in the following description and indicated in all the views of the drawings by the same reference characters.

The improved flash light forming the subject matter of the present invention comprises a supporting stand 5 having a tubular member 6 rigidly secured thereto and in

which is slidably mounted a plurality of telescopic sections 7 constituting a collapsible standard, as shown. Fastened in any suitable manner to the upper telescopic section of the standard, is a cup or receptacle 8 adapted to contain a quantity of magnesia or other material, said receptacle being provided with a removable cover 9 to which is secured a cap piece 10 having a laterally extending arm 11, said cap and arm being provided with intersecting passages, as shown. Secured to the upper telescopic section of the standard beneath the receptacle 8, is a supporting arm 12, to the free end of which is secured in any suitable manner, a torch 13, the latter being provided with a vertically disposed concavo-convex guard or shield 14. Engaging the free end of the arm 11, is a discharge nozzle 15 through which the magnesia or powder in the receptacle 8 is delivered to the torch 13. The nozzle 15 comprises a tubular body portion, the free end of which is flattened at 16 and provided on its lower side with a longitudinally disposed discharge slot 17 for directing the powder into the path of the flame. Seated in the bottom of the receptacle 8, is a nipple 18, the lower end of which is projected within the adjacent telescopic section 7, while the upper end thereof is bent downwardly in spaced relation to the bottom of the receptacle, as indicated at 19. Connected within the projecting end 20 of the nipple 18, is one end of a hose or other flexible conductor 21, which latter extends through all of the telescopic sections 7, the lower end of the conductor being connected with a valve 22 on an air tank 23. Disposed within the air tank 23, is a pump 24, the handle 25 of which projects above the top of the tank so that by closing the valve 22 and operating the handle 25, said tank may be filled with air. Each telescopic section 7 is provided with a screw or similar fastening device 26, which latter bears against the adjacent telescopic section and serves to lock said sections in either extended or retracted position.

In operation, the valve 22 is closed and the tank 23 pumped full of air. The telescopic sections 7 are then extended until the torch 13 has been adjusted to the proper height, after which the clamping screws 26 are tightened which holds the sections against accidental movement. After the torch 13 has been

lighted, the valve 22 is moved to open position, thus allowing a current of air to pass through the conductor 21 and nipple 18 into the receptacle 8, the magnesia or other material in said receptacle 8 being forced upwardly and laterally through the nozzle 15 and discharge orifice 17 in the path of the flame from the torch, thus to produce a flash light. By releasing the clamping screws 26, the telescopic sections may be housed within the lower section 6 so as to permit the device to be compactly nested for transportation or shipment.

In Fig 4 of the drawings, there is illustrated a modified form of the invention, in which the standard 7' is formed of a single section, and supported directly on the air tank 23', there being a tube 27 communicating with the interior of the tank at the top thereof for connection with an air pump, the construction and operation of the device being otherwise similar to that shown in Figs. 1 and 2 of the drawings.

Having thus described the invention, what is claimed as new is:

1. A flash light including an extensible standard formed of a plurality of telescopic sections, a powder receiving receptacle carried by one of the standard sections and provided with an overhanging nozzle, a torch supported by the standard, a nipple disposed within the receptacle, and a conductor extending through all of the standard sections and having one end thereof connected with said nipple and its other end projecting through the bottom standard section and communicating with a source of compressed air for forcing air within the receptacle, thereby to direct the powder into the path of the flame from the torch.

2. A flash light including a standard, a powder receiving receptacle carried by the standard, a cap secured to the receptacle, a nozzle engaging the cap and provided with a flattened portion having a discharge orifice formed in the bottom thereof, a torch secured to the standard, a nipple disposed within the receptacle and having one end thereof bent downwardly in spaced relation to the bottom of the receptacle, and means connected with the nipple for forcing air under pressure into said receptacle, thereby to discharge the powder through the orifice in the nozzle into the path of the flame from the torch.

3. A flash light including an extensible standard formed of a plurality of telescopic sections, a powder receiving receptacle carried by one of the sections and provided with a nozzle, a torch, and a flexible conductor extending through the telescopic sections and having one end thereof communicating with the interior of the powder receptacle and its other end connected with a source of compressed air for forcing the

powder through the discharge nozzle into the path of the flame from the torch.

4. A flash light including an extensible standard formed of a plurality of telescopic sections, a powder receiving receptacle carried by one of the sections and provided with an overhanging nozzle, a torch, a nipple disposed within the receptacle and having one end thereof bent downwardly and spaced from the bottom of the receptacle, a flexible conductor extending through the several sections of the standard and having one end thereof connected with the nipple and its other end operatively connected with a source of compressed air, and means for securing the telescopic sections in adjusted position.

5. A flash light including a supporting base having a tubular member secured thereto, a plurality of telescopic sections carried by the tubular member, a powder receiving receptacle carried by one of said sections and provided with an overhanging nozzle, a supporting arm secured to one of the sections beneath the powder receiving receptacle, a torch carried by said supporting arm, a shield secured to the torch, and a flexible conductor extending through all of said sections and having one end thereof communicating with the interior of the receptacle and its other end connected with a source of compressed air for forcing the powder through the nozzle into the path of the flame from the torch.

6. A flash light including a supporting base having a tubular member, a plurality of telescopic sections carried by the tubular member, a powder receiving receptacle secured to the upper section, a nozzle extending laterally from said receptacle and having one longitudinal edge thereof provided with a discharge orifice, a torch secured to and movable with the upper telescopic section, a nipple disposed within the receptacle and having one end thereof projecting within the adjacent telescopic section and its other end bent downwardly in spaced relation to the bottom of said receptacle, and a flexible conductor having one end thereof secured to the adjacent end of the nipple and its other end extending through the telescopic sections, tubular member and base for connection with a source of compressed air.

7. A flash light including a standard, a powder receiving receptacle secured to the standard, a cover engaging the receptacle and provided with a cap having a laterally extending arm, there being intersecting passages formed in the cap and arm, respectively, a nozzle engaging the arm and provided with a terminal flat portion having a slot formed in the bottom thereof, a torch secured to the standard, a nipple disposed within the receptacle and having one end

thereof bent downwardly and spaced from the bottom of said receptacle, means connected with the nipple for forcing air under pressure within said receptacle, thereby to direct the powder through the nozzle into the path of the flame from the torch, and means for controlling the passage of air to said receptacle.

In testimony whereof, we affix our signatures in presence of two witnesses.
